AUTOMATIC COMBUSTION CONTROL

Robert E. Bressler, Oregon, Ill., assignor to Kol-Master Corporation, Oregon, Ill., a corporation of Illinois

Application December 10, 1938, Serial No. 244,985

15 Claims. (Cl. 110—101)

This invention relates to improvements in automatic combustion controls and it consists of the matters hereinafter described and more particularly pointed out in the appended claims. The 5 improved control is herein illustrated and will be herein described as used in connection with a stoker for feeding solid fuel such as coal to a fuel bed and for supplying the air necessary to support combustion.

10 In stoker fed furnaces, the amount of coal that will be burned by a certain volume of air varies materially with the condition of the fuel bed. Also, the amount of coal that will be fed by the stoker, as when the screw or other mechanism 15 is operating at a certain rate will vary materially with several different factors, one of which is the amount of coal in the hopper causing a different quantity to be fed to the screw or other feed mechanism. The reason therefor is that the 20 depth of the coal over the screw or other mechanism varies, and much more coal will be fed by a full hopper than from one only half full.

The size of coal that is being supplied to the stoker will also make a large variation in the 25 amount of coal that would be fed and segregation of coal when it is delivered to the bin, even with prepared stoker coal, is such that variation of as much as 30% will be had in the amount of fuel being supplied to the burner when the feed 30 is set at the same setting when coarse or fine coal is being supplied.

Due to the factors above mentioned, it is impossible by hand operation to control accurately, either the coal or the air to produce proper combustion conditions. Therefore, it has always been 35 found that in operation of stokers, a thin fuel bed was the rule and that a large excess of air was supplied. Sometimes this excess runs as high as 200 to 300% so that the efficiency of the stokers is materially reduced as compared to what could 40 be had with proper control of both coal and air supply.

The depth of the fuel bed on the burner or retort determines the pressure of the air in the chamber beneath the fuel bed and this pressure varies with the depth or density of the fuel bed. There is a proper fuel bed depth for every size of 45 stoker and the fuel bed depth, required by the design of the burner, does not vary with various burning rates at which the fuel may be burned.

50 For proper operation of a stoker, the fuel bed should be maintained at an approximately exact depth independent of the rate at which the coal is being burned. The pressure in the wind box and chamber beneath the burner or retort will then be a fixed amount due to the fact that the given amount of fuel bed provides a fixed resistance by causing the feeding of coal to be varied either with increase or decrease of wind box pressure. Wind box pressure in a stoker as

used herein, is the pressure caused by the operation of the blower using a certain setting of the damper when the air is being delivered through a fuel bed of any particular depth. In this respect, the damper may be associated either with 5 the inlet or the discharge side of the blower.

One of the objects of the present invention is to provide an automatic combustion control which maintains a constant fuel bed and supplies a fixed volume of air therefor. 10

Another object of the invention is to provide a control which maintains a fixed burning rate and which rate may be readily adjusted to provide innumerable rates to suit conditions without difficulty or danger of too much fuel accumulation in 15 the furnace and at the same time reduce fly ash to a minimum.

A further object of the invention is to provide a control of this kind which maintains a fixed wind box pressure through control of fuel feed 20 to maintain a fixed fuel bed resistance, by means of the tendency of the wind box pressure to vary.

Again, it is an object of the invention to provide a control of this kind which employs wind box pressure to control coal feed to maintain 25 the wind box pressure constant within narrow limits.

Again, it is another object of the invention to provide a control which, if the fuel bed is thin, after a stand by period, causes a feed of coal at its 30 maximum feeding rate until the proper depth of bed is restored when the coal feed is operated to maintain that depth of fuel bed and to supply coal in accordance with the amount being burned with the volume of air supplied. 35

Again, it is a further object of the invention to provide an automatic combustion control for a stoker wherein no attention need be given the stoker except for the periodic removal of clinkers and supplying coal to the hopper. 40

The above mentioned objects of the invention, as well as others together with the several advantages thereof, will more fully appear as the specification proceeds.

In the drawing:

Fig. 1 is a diagrammatic view of the preferred 45 form of the invention in connection with a stoker for controlling the operation thereof.

Fig. 2 is a longitudinal vertical sectional view on a somewhat enlarged scale through the retort or burner of the stoker as taken on the line 2—2 50 of Fig. 1.

Fig. 3 is a vertical sectional view on an enlarged scale through a certain pressure switch embodied in the system and which will be later referred to. 55

Referring now in detail to the accompanying drawing, 5 indicates as a whole a conventional stoker including a fuel hopper 6, a burner or retort 7 and a conduit or tube 8 leading from the hopper to the burner. In the conduit 8 is 60

a screw 9 (see Fig. 2) for moving the fuel along the conduit into the burner with an underfeed action to pile up therein over the dead plates 10 to provide the fuel bed 11 of the desired depth. 5 The feed screw is rotated step by step by a drive mechanism enclosed in a casing 12 and this mechanism is driven through a suitable speed reducing mechanism 13 from a motor 14. The conduit 8 has a windbox 15 associated therewith 10 and one end of said windbox is made as an air chamber 16 in which the burner is disposed in a manner whereby air in said chamber passes into the burner and up through the fuel bed 11 therein to support combustion. In the discharge 15 duct of the blower, where it connects with the windbox, is a damper 15a operable from outside the windbox by a dial 15b. By means of said damper, the volume of air entering the windbox may be controlled. If desired, the damper may 20 be placed in the inlet side of the blower instead of where described. The other end of the windbox is operatively connected to the discharge side of a blower 17, the inlet side of which is hooded as at 18. Preferably, a second and smaller motor 19 is employed to drive the blower. By the use of the two separate motors as mentioned, it is possible to burn fuel at a lower rate at a small current cost. One side of the motor 19 is connected to one side of the other motor 14 by a 25 bridge or line 20.

The improved control includes a plurality of control elements, namely a temperature responsive element such as a thermostat 21 employed in the area or space to be heated and a limit control 22, usually placed in the bonnet of a hot air furnace when the stoker is employed with such a furnace. On a hot water furnace, said limit control is clamped to a pipe leading away from the boiler thereof. The control further 30 includes a transformer 23, a relay 24 with a 110V coil, a second relay 25 with a 24V coil, a motor driven time switch 26 with a short interval contacter and a longer interval contacter, a circuit breaker 27 which serves as an overload 35 protection for the coal feed motor and a pressure actuated switch 28.

The transformer 23 serves only to reduce the voltage in the circuit of the room thermostat 21 so that small wire may be used therefor, thus 40 simplifying installation. The relay 24 with the 110V coil controls the coal feed driving motor 14, the motor being energized when said relay is closed and deenergized when said relay is open. The relay 25 with the 24V coil is the starting 45 device for the blower motor 19 and also for the coal feed motor when the relay 24 is closed.

The time switch 26 serves two purposes. A part thereof closes once, say every 10 minutes and remains closed for a period of about a half 50 minute or less. This causes the coal feed motor 14 to operate once each 10 minutes when the thermostat 21 calls for heat independent of all other controls, except when the circuit breaker 27 is open or the limit control is off. When the 55 circuit breaker is open or when the limit control is off, said motor will not run. The other part of the interval contacter operates as a "hold fire" control, closing once each hour for about a minute, causing operation of the entire stoker 60 for that period except when the limit control is off or the circuit breaker is open.

The pressure switch 28, as shown in Fig. 3, is in the nature of a casing 29 containing a flexible diaphragm 30 open to atmosphere on one side 75 and responsive on the other side to the pressure

in the windbox 15 and chamber 16 by reason of a conduit 31 which connects one side of the casing to the windbox. The switch 28 may be mounted upon the stoker hopper. A tension device 32 is carried by the casing 29 to adjust the 5 pressure necessary to cause the switch to function under different conditions. A stem 33 moves with the diaphragm to open and close certain contacts as will appear later.

34 and 35 indicate respectively the main current conductors leading from a source of electrical energy or supply and secondary conductors 36-37 connect one of the coils or windings of the transformer 23 with said main conductors. The main conductor 34 is connected to 15 one side of the limit control 22 and the other side of said control is connected to one side of the coil of the relay 24 by a line 38 and in which is provided a contact 39. One side of the other coil or winding of the transformer 23 is connected to one side of the coil of the relay 25 by a line 40 and the other side of said other coil or winding of the transformer is connected to one side of the thermostat 21 by a line 41. The other side of the thermostat is connected by a line 42 25 with the other side of the coil of the relay 25.

Associated with the relay 24 is a contact 43 connected by a line 44 leading to the other side of the coal feed motor, the overload circuit breaker 27 being incorporated in said line 44. 30 The relays 24-25 each includes a normally open armature 24a-25a respectively which, when said relays are energized, are caused to engage the associated contacts 43 and 39 respectively before mentioned. The armature 24a is connected in 35 circuit to the main conductor 35 while the armature 25a is connected by a line 45 to the line 20 connecting one side of both motors 14 and 20 together. A branch line 35a connects the other side of the blower motor 19 with the main conductor 35.

The time switch 26 includes a pair of fixed contacts 46-46a and a second pair of contacts 47-47a, movable toward and away from the first mentioned ones periodically. As shown 45 herein, said switch includes a motor 48 that drives a shaft 48a, which carries cams 48b and 48c. These cams so engage the contacts 47-47a as to cause them to periodically engage and disengage said contacts 46-46a. The cam 48b is 50 of such formation that the contacts 46-47 engage once about every ten minutes for about $\frac{1}{2}$ a minute, but this time interval may be changed by providing the cam 48b with a different number of faces. The cam 48c is of such formation 55 that the contacts 46a-47a engage once about every 60 minutes for about one minute. The main conductor 35 leads to the contact 46 while the contact 47 is connected by a line 49 to the other side of the 110V coil of the relay 24. The contact 47a is connected by a line 41a to the line 41 and the contact 46a is connected by a line 42a to the line 42. Thus the contacts 46a-47a are 60 in the low voltage circuit and parallel with the thermostat.

The pressure switch 28 includes a movable contact support 50 carrying a contact 51 which is connected in circuit to the line 49 by a line 53. The support 50 is actuated by the stem 33 of the pressure switch for movement away from and 70 toward a fixed contact 52 which is connected in circuit to the line 44 by the line 56. When pressures on both sides of the diaphragm 30 are substantially the same, the contacts 51-52 are engaged. When the pressure on the bottom of the 75

diaphragm exceeds that on the top of the diaphragm, said contacts are disengaged.

In the operation of the control system, assume that the limit control is functioning within its 5 temperature range as a closed switch. Also, assume that the contacts 46-47 and 46a-47a of the timer switch 26 are out of engagement and that the thermostat 21 is in its "off" condition wherein it is not calling for heat. At this time 10 both motors 14 and 19 are deenergized and the pressure in the wind box 15 approximates atmospheric pressure so that the contacts 51-52 of the pressure switch 28 are engaged.

Now assume that the temperature in the space 15 to be heated is such that the thermostat 21 calls for heat and therefore closes. As the thermostat is closed, current flows through the secondary of the transformer 23, line 41, thermostat 21, line 42, coil of relay 25, line 40, thus completing the 20 circuit for the transformer.

This energizes the coil of the relay 25 to attract its armature 25a which engages contact 39. This establishes a circuit from line 34, limit control 22, contact 39, armature 25a, line 45 to 25 bridge 20, through the blower motor 19, line 35a to line 35, thus starting the blower into operation. Also, if relay 24 has its armature 24a engaged with the contact 43, current flows as before to bridge 20, through motor 14, line 44 (and circuit 30 breaker 27 therein which is closed) to contact 43, armature 24a to line 35, thus energizing the fuel or coal feed motor 14.

The relay coil 24 will be held in its energized 35 condition, with its armature 24a in engagement with the contact 43 so long as the contacts 51-52 of the pressure switch 28 are engaged due to low pressure conditions in the wind box. With the contacts 51-52 thus engaged, current flows from the line 34, through the limit control 22, line 38, 40 relay coil 24, line 49, contacts 51-52, line 56, line 44, contact 43, armature 24a to line 35. This holds the circuit for the relay coil 24 closed.

With the stoker in operation, fuel is being fed 45 to the burner or retort 7 and air under pressure is being delivered to said burner or retort to support combustion. As the pressure builds up 50 in the wind box, the contacts 51-52 separate, opening the holding circuit for the relay coil 24 so that the armature 24a disengages the contact 55 43. This opens the circuit for the fuel feed motor 14 so that it stops the feeding of fuel. Later reengagement of the contacts 51-52 will not energize the relay coil 24 because there is no circuit to line 35 except when relay coil 24 is energized.

Thus even though windbox pressure may drop 60 to cause engagement of the contacts 51-52 the feed motor 14 will not operate until the relay coil 24 is energized by another circuit.

Closing of the circuit for the relay coil 24 is 65 accomplished periodically by the constantly operating time switch 26. Every few minutes the cam 48b of the time switch 26 will cause engagement of the contacts 46-47 so that current will then flow from line 34, through limit control 22, line 38, relay coil 24, line 49, contacts 47-46 to line 35 so that the relay coil 24 becomes energized. This causes the armature 24a to engage the contact 43, permitting the switch 70 28 through the contacts 51-52 to maintain current flow through the relay coil 24 and energizing the coal feed motor 14 as before described. Thus, a differential in time is used for the starting 75 of the fuel feed motor 14 and a differential in pressure is used for stopping said motor.

In the operation of the time switch 26, it functions through the cam 48c to engage the contacts 46a-47a which forms the "hold fire" control of the system. As these contacts are in parallel 5 with the thermostat 21, the engagement of the said contacts produces the same function as the closing of the thermostat 21 when it calls for heat. Should the limit control 22 be in its "off" condition, current from the line 34 cannot pass to any of the before mentioned parts so that the 10 stoker will not operate under that condition.

It is important that the fuel feeding motor 14 should start whenever the thermostat 21 or the "hold fire" control (as caused by the engagement of the contacts 46a-47a) is calling for 15 operation and this is accomplished as follows: When the relay coil 25 is in its deenergized condition, current will flow from line 34, control 22, line 38, relay coil 24, line 49, line 53, contacts 51-52 (which because blower motor 19 is not 20 operating will be in the engaged condition) through line 56, circuit breaker 27, line 44, motor 14, bridge 20, motor 19, line 35a, line 35 completing the circuit to energize the relay coil 24 and then hold it in closed position until the thermostat 21 or "hold fire" control calls for stoker operation. This circuit is possible because there is no 25 resistance to the very small amount of current passed by the relay coil 24 due to the resistance of both motors 14 and 19 when not in operation and this small amount of current is not sufficient 30 to cause operation of said motors.

When the thermostat 21 calls for heat or when the "hold fire" control calls for operation of the 35 stoker, this energizes the relay coil 25 as before described and causes the engagement of its armature 25a with the contact 39. The motor 19 then starts to drive the blower and to build up a resistance in the last described circuit, after which the control of the fuel feed motor 14 will 40 be effected or come through the time switch 26 and the pressure switch 28. It is apparent from the above, that the fuel feed motor 14 is started and stopped to control the fuel bed depth, instead 45 of varying the feeding of fuel as in most conventional stokers.

It is pointed out at this time that the amount of fuel which can be consumed after the pressure switch 28 functions to separate the contacts 51-52 and previous to the time that the 50 time switch 26 will start another cycle of a feeding of coal to the fuel bed, will not be sufficient to change the depth of the fuel bed to any appreciable extent. However, it is desirable that the rate of fuel feed be higher than the rate of 55 combustion of fuel. The reason therefor is in order to provide against coking of the fuel in the retort and to vary the depth of the fuel somewhat at each operation so that the amount of fuel being fed is sufficient to break up the fuel bed, each 60 time fuel is being fed. The comparative short time which is permitted between operations by the switch 26 after the closing of the pressure switch contacts 51-52 is not sufficient to disturb the correct functioning of the stoker nor is the 65 amount of coal fed by the operation of the switch 26 should the pressure switch not be calling for fuel, sufficient to disrupt the operation of the stoker.

By operating the device 32 of the pressure 70 switch, the diaphragm 30 may be set to function at the desired windbox pressure and which windbox pressure may be determined by adjusting the damper 15a and thus determine the burning rate 75 of the stoker.

After a standby period, if the fuel bed is thin, the stoker is caused to feed coal at its maximum rate until the fuel bed has been brought up to its proper depth after which the fuel feed is operative only to an extent as will maintain that depth of fuel bed and to supply coal in accordance with the amount thereof being burned with the volume of air being supplied.

It is apparent from the above that through control of the fuel feed to maintain a constant depth of fuel bed, a fixed resistance to passage of air therethrough is obtained so that the windbox pressure is maintained constant and this constant resistance is obtained by the tendency of the windbox pressure to vary in accordance with varying depth of fuel bed and this depth is maintained constant independent of the burning rate.

When the thermostat 21 is satisfied with heat, it opens the circuit to the relay coil 28 so that the stoker stops.

While in describing the invention I have referred in detail to the form, arrangement and construction of the various parts involved, the same is to be considered only in the illustrative sense so that I do not wish to be limited thereto except as may be specifically set forth in the appended claims.

I claim as my invention:

30 1. In combination with means providing a retort adapted to support a fuel bed, means for feeding fuel to said retort to build up the bed to a desired depth, means for delivering air under pressure through said fuel bed to support combustion thereof, said bed offering a resistance to said air so that its pressure varies with the depth or density of the fuel bed, a circuit for said fuel feeding means and for said air delivering means respectively, means dependent upon the demand for heat and operating through a part of said circuit for starting said air delivering means, pressure responsive means operative at one pressure of the delivered air for closing another part of said circuit for holding said feeding means in operation and operating at another pressure of the delivered air for stopping said feeding means, and means operating automatically through another part of said circuit at predetermined timed intervals for restarting said fuel feeding means independently of said pressure responsive means when said means dependent upon demand for heat is holding said air delivering means in operation.

55 2. In combination with means providing a retort adapted to support a fuel bed, means for feeding fuel to said retort to build up the bed to a desired depth, means for delivering air under pressure through said fuel bed to support combustion thereof, said bed offering a resistance to said air so that its pressure varies with the depth or density of the fuel bed, a circuit for said fuel feeding means and said air delivering means respectively, means dependent upon the demand for heat and operating through a part of said circuit for starting said air delivering means, pressure responsive means operative at one pressure of the delivered air for closing another part of said circuit for holding said feeding means in operation and operating at another pressure of the delivered air for stopping said feeding means, and means operating automatically through another part of said circuit at predetermined timed intervals for restarting said fuel feeding means independently of said pressure responsive means when said means dependent upon demand for

heat is holding said air delivering means in operation, and means independent of said means dependent upon demand for heat for controlling said circuit for said fuel feeding means and said air delivering means respectively.

5 3. In combination with means providing a retort adapted to support a fuel bed, fuel feeding means and means for driving the same to build up the fuel bed to a desired depth, means operable to provide air under pressure for delivery through said fuel bed to support combustion thereof, said bed offering a resistance to said air so that its pressure varies with the depth or density of the fuel bed, means for driving said air delivery means, a circuit for both of said driving means, means dependent upon the demand for heat and operating through a part of said circuit for starting said driving means for the air delivering means, pressure responsive means operating at one pressure of the delivered air for closing another part of said circuit for holding said driving means for the fuel feeding means in operation, and operating at another pressure of the delivered air for stopping said fuel feed driving means, and means operating automatically through another part of said circuit at predetermined timed intervals for restarting said fuel feed driving means independently of said pressure responsive means when said means dependent upon the demand for heat is holding said air delivering means in operation.

4. In combination with means providing a retort adapted to support a fuel bed, fuel feeding means and means for driving the same to build up the fuel bed to a desired depth, means operable to provide air under pressure for delivery through said fuel bed to support combustion thereof, said bed offering a resistance to said air so that its pressure varies with the depth or density of the fuel bed, means for driving said air delivery means, a circuit for both of said driving means, means dependent upon the demand for heat and operating through a part of said circuit for starting said driving means for the air delivering means, pressure responsive means operating at one pressure of the delivered air for closing another part of said circuit for holding said driving means for the fuel feeding means in operation, and operating at another pressure of the delivered air for stopping said fuel feed driving means, and means operating automatically through another part of said circuit, at predetermined timed intervals for restarting said fuel feed driving means independently of said pressure responsive means when said means dependent upon the demand for heat is holding said air delivering means in operation, and means independent of said means dependent upon the demand for heat for controlling said circuit for said fuel feeding means and said air delivering means respectively.

60 5. In combination with means providing a retort adapted to support a fuel bed, means for feeding fuel to said retort to build up the bed to a desired depth, a motor for driving said fuel feeding means, means operatively connected to the retort for delivering air under pressure through the fuel bed to support combustion thereof, said bed offering a resistance to said air so that its pressure varies with the depth or density of the fuel bed, a second motor for driving the air delivery means, a circuit for both of said motors, means dependent upon the demand for heat and operating through a part of said circuit for starting said second motor, pressure responsive means operating at one pressure of the de-

livered air for closing another part of said circuit for holding said first mentioned motor in operation and operating at another pressure of the delivered air for stopping said first mentioned motor, and means operating automatically through another part of said circuit, at predetermined timed intervals for restarting said first mentioned motor independently of said pressure responsive means when said means dependent upon the demand for heat is holding said second mentioned motor in operation.

6. In combination with means providing a retort adapted to support a fuel bed, means for feeding fuel to said retort to build up the bed to a desired depth, a motor for driving said fuel feeding means, a blower operatively connected to the retort for delivering air under pressure through the fuel bed to support combustion thereof, said bed offering a resistance to said air so that its pressure varies with the depth or density of the fuel bed, a second motor for driving said blower, a circuit for both of said motors, means dependent upon the demand for heat and operating through a part of said circuit for starting the blower motor, pressure responsive means operating at one pressure of the delivered air for closing a part of said circuit for holding the motor for the fuel feeding means in operation and operative at another pressure of the delivered air for stopping said motor for the fuel feeding means, and means operating automatically through another part of said circuit at predetermined timed intervals for restarting the last mentioned motor independently of said pressure responsive means when said means dependent upon the demand for heat is holding the blower motor in operation.

7. In combination with means providing a retort adapted to support a fuel bed, means for feeding fuel to said retort to build up the bed to a desired depth, means for delivering air under pressure through said fuel bed to support combustion thereof, said bed offering a resistance to said air so that its pressure varies with the depth or density of the fuel bed, a circuit for said fuel feeding means and said air delivering means respectively, means dependent upon the demand for heat and operating through a part of said circuit for starting said air delivering means, pressure responsive means operative at one pressure of the delivered air for closing another part of said circuit for holding said feeding means in operation and operating at another pressure of the delivered air for stopping said feeding means, and means operating automatically through another part of said circuit, at predetermined timed intervals for restarting said fuel feeding means independently of said pressure responsive means when said means dependent upon demand for heat is holding said air delivering means in operation, and means for regulating the pressure of the air delivered to said retort to control the burning rate of the fuel bed.

8. In combination with means providing a retort adapted to support a fuel bed, means for feeding fuel to said retort to build up the bed to a desired depth, means for delivering air under pressure through said fuel bed to support combustion thereof, said bed offering a resistance to said air so that its pressure varies with the depth or density of the fuel bed, a circuit for said fuel feeding means and said air delivering means respectively, means dependent upon the demand for heat and operating through a part of said circuit for starting said air delivering means,

pressure responsive means operative at one pressure of the delivered air for closing another part of said circuit for holding said feeding means in operation and operating at another pressure of the delivered air for stopping said feeding means, and means operating automatically through another part of said circuit, at predetermined timed intervals for restarting said fuel feeding means independently of said pressure responsive means when said means dependent upon demand for heat is holding said air delivering means in operation, means for regulating the pressure of air delivered to said retort to control the burning rate of the fuel bed, and means for adjusting the operative pressure of said pressure responsive means.

9. In combination with means providing a retort adapted to support a fuel bed, fuel feeding means and a motor for driving the same to build up the fuel bed to the desired depth, a circuit for said motor, means for delivering air under pressure to said fuel bed to support combustion thereof, said bed offering a resistance to said air so that its pressure varies with the depth or density of the fuel bed, means dependent upon the demand for heat for starting the air delivering means into operation, pressure responsive means operating at one pressure of the delivered air for holding the motor circuit closed and operating at another pressure of the delivered air for opening said motor circuit, and means operating automatically at predetermined timed intervals for closing said motor circuit independently of said pressure responsive means when said means dependent upon the demand for heat is holding said air delivering means in operation.

10. In combination with means providing a retort adapted to support a fuel bed, fuel feeding means and a motor for driving the same to build up the fuel bed to the desired depth, a circuit for said motor, means for delivering air under pressure to said fuel bed to support combustion thereof, said bed offering a resistance to said air so that its pressure varies with the depth or density of the fuel bed, means dependent upon the demand for heat for starting the air delivering means into operation, pressure responsive means operating at one pressure of the delivered air for holding the motor circuit closed and operating at another pressure of the delivered air for opening said motor circuit, and means operating automatically at predetermined timed intervals for closing said motor circuit independently of said pressure responsive means when said means dependent upon the demand for heat is holding said air delivering means in operation, and means for regulating the pressure of the air delivered to said retort to control the burning rate of the fuel bed.

11. In combination with a stoker including a retort adapted to support a bed of fuel thereon, a means for feeding fuel to the retort to build up the bed to the desired depth, a motor for driving said means, a blower and a motor for driving the same and a windbox connecting said blower and the retort to deliver air under pressure to said retort for passing through the fuel bed, said bed offering a resistance to the passage of air therethrough so that said pressure varies with the depth or density of the fuel bed, said blower motor being connected in a part of the circuit for the first mentioned motor, means dependent upon the demand for heat for closing that part of said circuit associated with the blower motor for

starting said motor, means responsive to windbox pressure and operating at one pressure of the air therein for closing that part of said circuit to hold the fuel feed driving motor in operation, and 5 operating at another pressure of the air in the windbox for stopping said motor, and means operating automatically through said circuit at predetermined timed intervals for restarting the fuel feed driving motor independently of said 10 pressure responsive means, when said blower motor circuit is being held closed by said means responsive to the demand for heat.

12. In combination with a stoker including a retort adapted to support a bed of fuel thereon, 15 means for feeding fuel to the retort to build up said bed to the desired depth, a motor for driving said means, a blower and a motor for driving the same and a windbox connecting the blower and the retort to supply air under pressure to said 20 retort for passing through the fuel bed to support combustion thereof, said bed offering a resistance to the passage of air therethrough so that the pressure in the windbox varies with the depth or density of the fuel bed, a circuit for both of said 25 motors, means dependent upon the demand for heat for closing that part of said circuit which will start said blower motor, means responsive to the pressure in the windbox and operative at one 30 pressure therein for closing that part of said circuit that will hold the fuel feeding means driving motor in operation and operative at another pressure in the windbox for opening said part of the circuit to stop said fuel feeding means driving motor, and a constantly running time switch 35 for closing said last mentioned part of said circuit at relatively short intervals to restart said fuel feeding means driving motor independently of said pressure responsive means when said first mentioned part of the circuit is being held closed 40 by said means dependent upon the demand for heat.

13. In combination with a stoker including a retort adapted to support a bed of fuel thereon, 45 means for feeding fuel to the retort to build up said bed to the desired depth, a motor for driving said means, a blower and a motor for driving the same and a windbox connecting the blower and the retort to supply air under pressure to said retort for passing through the fuel bed, said bed 50 offering a resistance to the passage of air therethrough so that the pressure in the windbox varies with the depth or density of the fuel bed, a circuit for said motors, means dependent upon the demand for heat for closing that part 55 of said circuit which will start said blower motor, means responsive to the pressure in the windbox and operative at one pressure therein for closing that part of said circuit that will hold the fuel feeding means driving motor in operation and 60 operative at another pressure in the windbox for opening said part of the circuit to stop said fuel feeding means driving motor, a constantly running time switch for closing said last mentioned part of said circuit at relatively short intervals 65 to restart said fuel feeding means driving motor independently of said pressure responsive means when said first mentioned part of the circuit is being held closed by said means dependent upon the demand for heat, and means for regulating the pressure of the air delivered by the blower to 70 the retort to control the burning rate of the fuel bed.

14. In combination with a stoker including a

retort adapted to support a bed of fuel thereon, means for feeding fuel to the retort to build up said bed to the desired depth, a motor for driving said means, a blower and a motor for driving the same and a windbox connecting the blower and the retort to supply air under pressure to said retort for passing through the fuel bed, said bed offering a resistance to the passage of air therethrough so that the pressure in the windbox varies with the depth or density of the fuel bed, a circuit for said motors, a relay in that part of said circuit associated with the blower motor and controlling said part of said circuit, a second relay in another part of said circuit associated with the fuel feeding means driving motor, means dependent upon the demand for heat and causing said first mentioned relay to close its associated part of the circuit to start the blower motor, means responsive to windbox pressure and operative at one pressure to energize said second relay 20 to close that part of the circuit associated with the fuel feeding means driving motor whereby said motor is held in operation, said pressure responsive means operating at another pressure in the windbox for deenergizing said second relay 25 to stop the last mentioned motor, and a constantly running time switch operating at intervals for energizing said second relay independently of said pressure responsive means to restart said fuel feeding means driving motor when 30 said first mentioned relay is being held closed by said means responsive to the demand for heat.

15. In combination with a stoker including a retort adapted to support a bed of fuel thereon, 35 means for feeding fuel to the retort to build up said bed to the desired depth, a motor for driving said means, a blower and a motor for driving the same and a windbox connecting the blower and the retort to supply air under pressure to said retort for passing through the fuel bed, said bed 40 offering a resistance to the passage of air therethrough so that the pressure in the windbox varies with the depth or density of the fuel bed, a circuit for said motors, a relay in that part of said circuit associated with the blower motor and controlling said part of said circuit, a second relay in another part of said circuit associated with the fuel feeding means driving motor, means dependent upon the demand for heat and causing said 45 first mentioned relay to close its associated part of the circuit to start the blower motor, means responsive to windbox pressure and operative at one pressure to energize said second relay to close that part of the circuit associated with the fuel feeding means driving motor whereby said motor 50 is held in operation, said pressure responsive means operating at another pressure in the windbox for deenergizing said second relay to stop the last mentioned motor, and a constantly running time switch operating at intervals for energizing said second relay independently of said 55 pressure responsive means to restart said fuel feeding means driving motor when said first mentioned relay is being held closed by said means responsive to the demand for heat, said circuit 60 being arranged to close the relay for the driving motor for the fuel feeding means when said blower motor is inoperative so that said fuel feeding means driving motor will become energized by said means dependent upon the demand for heat 65 when the latter operates to cause its relay to close its associated part of the circuit.

ROBERT E. BRESSLER.
